UNITED STATES PATENT OFFICE.

THOMAS H. COCHRANE, OF JERSEY CITY, NEW JERSEY.

LOCOMOTIVE-CRANE SANDER.

1,340,016.

Specification of Letters Patent. Patented May 11, 1920.

Application filed July 24, 1919. Serial No. 312,953.

To all whom it may concern:

Be it known that I, THOMAS H. COCHRANE, a citizen of the United States, and a resident of the city of Jersey City, in the 5 county of Hudson and State of New Jersey, have invented a new and Improved Locomotive-Crane Sander, of which the following is a full, clear, and exact description.

10 This invention relates to railroad track sander, and more particularly to a track sander device for use on locomotive cranes.

An object of the invention is to provide 15 a track sander device which is readily attachable to a locomotive crane of present day use.

It is a purpose to provide the design of 20 a railway track sanding device which will adequately function on a locomotive crane to the same effect and for the same purpose as the sanding device now applied to ordinary locomotives.

Heretofore it has been difficult to provide 25 a railway crane with a track sanding device for the reason that a locomotive crane comprises a turn-table upon which the crane machinery and other parts are mounted. It has been somewhat difficult to provide a 30 sander device on the turn-table because the turn-table of the crane operates from many different angles, and the mechanical exigencies are such that the sander mechanism cannot be mounted beneath the turn-table of the 35 crane or on the stationary frame of the car carrying the crane.

This invention provides the necessary mechanical design for effecting the aforesaid purpose and for supplying a mechanism which may be installed on the turn-table of 40 the crane and on the frame of the car, and be under the direct control of the locomotive crane engineer.

With the above principal object in view 45 and others, the invention has relation to the several locomotive crane sander designs as set forth in the claims appended hereto, described in the following specification, and portrayed in the accompanying drawings:

Figure 1 shows a conventional type locomotive crane in side elevation, and illustrates in a general way a crane upon which the sander mechanism is installed.

Fig. 2 illustrates a diagrammatical plan view presented to disclose the general organization of parts of the invention.

Fig. 3 illustrates a fragmentary detailed view of parts of the sander mechanism, with some parts thereof shown in sectional views.

Fig. 4 discloses a valve depressor member employed to operate a main sander valve. 60

Fig. 5 illustrates a vertical sectional view through the king-pin or center of rotation of the locomotive crane turn-table.

Fig. 6 illustrates a manually controlled device used by the engineer for sanding 65 the tracks.

The Fig. 3 illustrates a pneumatic control mechanism employed by the engineer for sanding the track; while the Fig. 6 illustrates a manually controlled device for 70 effecting the same purpose.

A sander mechanism, such as here described, employs an air reservoir connected to the main crane air line of the air brake system as now used on practically all railroad and train equipment. Pipe connections joined with the air reservoir are provided with valves to control a pneumatic motor for opening an air sander valve to eject sand upon the track from a sand box. 80 The present invention also discloses a manually operated device to supplant the pneumatic motor.

Referring now more particularly to the drawings, the numeral 7 designates the locomotive frame which is carried over the car trucks 8. The frame 7 is equipped with a platform 9 upon which is mounted a suitable circular track to rotatively carry the locomotive crane and turn-table. The locomotive 90 crane primarily consists of a turn-table 10 which mounts the boiler house and engineer's cab. The usual form of crane 12 is provided and accessory parts such as cable, sheaves, and hoisting mechanism are mounted on the 95 turn-table 10.

The usual geared transmission is employed to drive the locomotive crane along the railroad track and consists of the drive pinion 13 and gears 14 which transmit power to the 100 trucks of the car mounting the frame. The turn-table 10 is usually centered by a king-pin 15, the king-pin acting to confine the frame 10 over the track and rollers 16. The king-pin 15 is usually drilled through the 105 center to provide a hole therethrough which accommodates an air pipe 17. This air pipe 17 connects with a pipe 18, which in turn connects with a main reservoir 19. The main air reservoir 19 is installed on the turn- 110

table 10 and is employed to furnish air to the brake system of the locomotive. A 5 brake valve 20 is included in the pipe 18 and conveniently positioned within the engineer's cab to enable him to apply the 10 brakes to the locomotive. Below the turn-table the pipe 17 connects with a pipe 22 which in turn connects to the auxiliary reservoir 23. This reservoir communicates 15 through a pipe 24 to the brake cylinder 25 as is the usual practice in train air brake systems. This arrangement permits the air 20 brake control to be located on the turn-table while the air brake mechanism is installed 25 on the car frame 7.

The above description presents a résumé 25 of a locomotive crane of standard design in present use. Since parts of this invention combine with parts of the air brake system 30 of the above described locomotive crane, it is thought advisable to present the above description in order that a comprehensible understanding of my invention may be gained. A description will now be given, in the following specification of my track sander attachment for use on locomotive cranes.

An air sander reservoir 27 is connected 35 to the pipe 24, and a check valve 28 is interposed between the air sander reservoir 40 and the pipe 24. This check valve is shown 45 in the Figs. 2 and 3, and is designed to permit air to enter the air sander reservoir but will restrain the air from discharging back into the pipe 24. The air sander reservoir 50 has connected therewith a pipe line 29 which connects with sander valve 30 of the sander 55 boxes 31. It is usual to provide one sand box 31 for each rail of the track to be sanded and each sand box is disposed over each rail 60 and attached to the structure of the frame 65. Each sand box is provided with a depending nozzle 32 which transmits sand from the valve 30 to the rails of the track. The lower portion of each nozzle 32 is positioned 70 to discharge the sand directly under the 75 wheels on the track.

An air release valve 33 is connected in 80 each branch of the pipe line 29. Each valve consists of a valve stem with a head 85 34. Means are provided for opening either one or both valves 33 in order to admit air passage from the reservoir 27 through the sander valve 30 to eject sand from the box 31 to the track.

Underneath the turn-table 10 are suspended 90 valve depressor plates 36 arranged concentric with the king-pin 15 of the locomotive crane. A pair of valve depressors are suspended on hangers 37 which 95 have their upper ends pivotally connected with the frame work of the turn-table 10 and the lower ends thereof pivotally connected with the valve depressor plates. A 100 number of coil springs 38 connect with the 105 valve depressor and the frame to normally

support the valve depressor in spaced relation from the valve head 34. A link 39 pivotally connects with each depressor plate 36 and with a bell crank 40. A pneumatic motor 41 connects with the bell crank 40 110 and acts to thrust the depressor plate downwardly against head of the valve to permit air pressure to pass through the pipe line 29 to act upon the sander valve 30. A pneumatic motor is employed for operating each 115 valve depressor plate. An air pipe 42 connects each pneumatic motor with the air 120 brake pipe line 18, and a valve 43 is included in each pipe 42 and accessively located within the engineer's cab in order 125 that he may open either one or both valves 130 43 at will.

When the engineer opens one or both of the valves 43 air flows from the air brake pipe 18 to either one or both of the pneumatic 135 motors. The pneumatic motors function to depress the plates 36 downwardly which opens the valves 33 and admits the air stored under pressure to flow from the air 140 sander reservoir 27 through the sander 145 valves 30 which ejects sand upon the rails under the locomotive drive wheels. When the valve 43 is turned back to normal position the motor 41 and springs 38 act to lift the valve depressors 36 out of engagement 150 with the valve 34 and thus the sanding of the track is discontinued. The locomotive 155 crane turn-table 10 may revolve at will about the king-pin center, yet the track can be sanded from any position of the locomotive 160 crane since the concentric plates 36 are at all times disposed over the valves 33. The valve depressors 36 have a peripheral 165 length of about equal to the practical range 170 of rotation of the crane.

Fig. 6 discloses a manually operated device whereby the engineer may displace a 175 lever 45 back and forth to actuate a link 46 to move a cross arm 47. The cross arm 47 is connected with the valve depressors 36 180 through hangers 37 in a manner similar to the above described design. This apparatus provides a manually operated means 185 which may displace the pneumatic control means where it becomes more practical to 190 employ the lastly described device.

A locomotive crane equipped with an adequate track sanding device works more effectively in clearing tracks and performing other work incident to railroad activities. It often happens that locomotive 195 cranes are used in lifting wrecked cars or locomotives from embankments and from tracks, and in executing this work the crane is often hampered in its movement along 200 the track because of slippery rails; and it is to avert this trouble that the present form 205 of locomotive crane track sander is presented herewith.

Having thus described my invention 210

what I claim as new and desire to secure by Letters Patent is:

1. A track sanding system as applied to the turn-table of a locomotive crane, comprising in combination; an air sander reservoir connected with any appropriate air supply, sand boxes, a pipe connecting the air sanding reservoir with the sand boxes, a valve included in the pipe, and means associated with the turn-table for opening the valve to sand a track from the turn-table, throughout any rotated position of the turn-table.
2. A track sanding system as applied to the turn-table of a locomotive crane, comprising in combination; an air sander reservoir connected with any appropriate air supply, sand boxes, a pipe connecting the air sanding reservoir with the sand boxes, a valve included in the pipe, and means associated with the turn-table for opening the valve, the herein described mechanism operable throughout any rotated position of the turn-table.
3. A locomotive sander mounted on the frame and on the turn-table of a locomotive crane, said sander comprising in combination; a pair of valve actuating members mounted on the locomotive crane concentric with the rotating center of the turn-table, means for operating the valve actuating members, an air pressure reservoir, a sand box, pipe connections joining the sand box and air reservoir, and a valve included in the pipe to transmit air from the reservoir to the sand box to eject sand therefrom for sanding the track from any rotated position of the turn-table.
4. A track sanding mechanism for locomotive cranes, comprising in combination; valve depressors, a pneumatic motor associated therewith to actuate said depressors, air supply means for the pneumatic motor, a sand box arranged to eject sand upon the track, an air sander reservoir, a pipe connecting the air sander reservoir with the sand box, and a valve included in the pipe and disposed beneath the valve depressor and adapted to be opened by said depressor for admitting air pressure to the sand box.

5. A locomotive crane sander designed for installation on the turn-table and car frame of said locomotive, comprising in combination; track sanding means installed on the locomotive frame, and mechanism mounted on the turn-table to govern the track sander means from any rotated position of the turn-table.

6. A locomotive sander designed for installation on the turn-table of a locomotive crane and on the frame of the locomotive truck, comprising in combination; track sander means installed on the locomotive truck frame, and a device installed on the turn-table for controlling the track sander means in order that an engineer may sand the track from the turn-table regardless of any rotated position of said turn-table.

7. A track sander for a locomotive crane, and adapted to be installed on the locomotive truck frame, and on the turn-table of said locomotive crane, comprising in combination; an air brake system for locomotives, consisting of an auxiliary reservoir, and a brake cylinder, a pipe connecting the auxiliary reservoir and brake cylinder; an air sander reservoir connecting with the pipe, sand boxes mounted on the locomotive truck frame, an air pipe connecting the air sander reservoir with each sanding box, an air valve included in the air pipe for regulating the flow of air to each sand box, and means associated with the turn-table of the locomotive crane for opening either one or both of the valves.

8. A sander for locomotive cranes where the crane is carried on a turn table upon the locomotive frame, comprising, in combination a sand box, an air reservoir, a pipe connecting the sand box and air reservoir, a valve included in the pipe to govern the flow of air to the sand box, a valve operating mechanism associated with the turn table for opening the valve from any relative working position of the turn table, and means for moving the valve operating mechanism in order to sand the track irrespective of the rotated position of the turn-table.

THOMAS H. COCHRANE.
